UNITED STATES PATENT OFFICE

CYRIL JOSEPH WILSON, OF EDEBASTON, BIRMINGHAM, ENGLAND, ASSIGNOR TO ASSOCIATED ICE & DAIRIES LIMITED, OF MANCHESTER, ENGLAND, A BRITISH COMPANY

PRODUCTION OF PAPER OR LIKE CARTONS OR RECEPTACLES

Application filed July 10, 1930, Serial No. 467,051, and in Great Britain July 13, 1929.

This invention has reference to paper, cardboard or like cartons, receptacles or containers (such as used for containing milk) of the kind that comprise a tubular body which is produced by the formation of a tube from an appropriately-shaped blank, one edge of which is gummed or glued to enable the making of a lap joint by the application of pressure to the outside of the region of jointure after the ungummed edge has been made to overlap the gummed edge by a body-forming machine. In the case of milk-cartons of this kind the body is completed by securing a bottom or closure to one end, dipping the same in molten wax or the like, or otherwise coating or proofing the interior with such wax to render the carton liquid-tight and to internally seal the joint. But according to the usual method of production, the strip of gum or other adhesive used for securing together the overlapping edges of the body-blank is either applied to the whole width of the overlap, or may be caused to spread over the said whole width under the pressure used in making the joint, so that there is always the risk or possibility of some of the adhesive exuding or being displaced beyond the region of jointure into the interior, and onto the exterior, of the tube, and of this exuded or displaced adhesive not being adequately isolated from the eventual contents of the carton by the internal waxing. The exuding of gum onto the outside of the tube is also objectionable. The principal object of the present invention is to provide for the making of internally-waxed or proofed carton or container bodies in a manner which ensures the complete or adequate isolation of the jointing adhesive from the interior of the tube and from the eventual contents of the carton, this object being realized according to the said invention by making the gummed or glued joint in such a manner that, in the completed joint, a web or substantial width of the underlap edge of the body blank is left free of, or kept unattached or ungummed to, the overlap edge along the inside of the formed tube. That is to say, the adhesive is so applied, and the joint is so made, that

the spread of the said adhesive under the joint-making pressure is limited or restricted to the region of the overlap nearest the outside of the tube, leaving a substantial width of the underlap material, inwards of 55 the gumming, loose or unconnected, so that when the tube is subsequently dipped or treated with wax or other proofing, the molten or fluid wax or the like is permitted access between the unattached web or strip 60 of underlap and the corresponding portion of the overlap so that the said wax, on hardening or setting, makes, along the whole length of the joint, a sealing-strip of such substantial thickness and/or width as adequately to isolate the adhesive material, or to 65 interpose an adequate barrier of wax or proofing material between the adhesive and the interior of the tube.

With reference to the accompanying drawing,

Fig. 1 shows a carton body made according to this invention, parts being broken away to show the manner of sealing.

Fig. 2 is a section of the joint before waxing.

Fig. 3 is a section on an enlarged scale, showing the joint as completed by the internal waxing of a carton.

Fig. 4 shows parts of an apparatus for pressing the joint.

Fig. 5 is a section similar to Fig. 3, of the carton made on the apparatus of Fig. 4.

A carton-body having a gummed and wax-sealed joint possessing the above-mentioned characteristics is shown in Figure 1 of the accompanying drawing where *a* represents the gummed region adjoining the outside of the body and *b* represents the strip or length of gum-isolating wax between the said gummed region and the inside of the said body.

A joint of this kind may be made by applying a relatively-narrow strip of gum or adhesive along a width of the underlap portion of the body-forming blank at a substantial distance inwards of and parallel with the edge of the said underlap. The width of the strip of gum as first applied, and its distance from the extreme edge of the underlap, are so predetermined as to ensure that the spread

of the gum under the joint-making pressure will still leave free or unattached from the overlap, a width of the underlap material sufficient to provide for the eventual adequate 5 wax-sealing or isolation of the adhesive from the inside of the tube. Preferably also the gum is applied so as to safeguard against spreading to the outside of the formed tube under the sealing pressure, which may be 10 done by allowing the gum to become partly dry or tacky before sealing pressure is applied to the joint.

For example, and as shown in Figures 2 and 3 the carton body-blank may be shaped 15 in a rotary machine which is adapted to grip the edge c^1 of the portion c of the blank that constitutes the underlap of the joint so that, on completion of the body-forming operation, an in-turned lip is left along the said 20 edge c^1 . Prior to the shaping operation, a strip of gum d is applied to the outside of the blank at such a distance from the edge c^1 that, after subjection to the joint-making pressure, the spread of the gum in the inward 25 direction will still leave free or unattached from the overlap e a strip of the underlap c , inwards of the gumming, as shown in Figure 2. Consequently, when the inside of the 30 carton having a body-joint made as described is internally waxed or treated with molten 35 proofing material, the said wax is enabled to permeate, and eventually set or harden, between the free strip of underlap and the overlap, and so form the wax barrier g for isolating the adhesive from the interior of the 40 carton.

Where the body is formed on a machine having a stationary mandril, the mandril may, as shown in Figure 4, be formed with a 45 longitudinal recess f so located that, at the moment when the joint-forming tool h operates, the said recess comes below the part of the underlap (inwards of the gummed strip e) which is to be left free or unattached from 50 the overlap. This enables, on the eventually internal waxing of the carton, the making of a lap-joint as shown in Figure 5, where the wax barrier-strip that isolates the gum d from the inside of the carton is again indicated by g .

Having described my invention, what I claim and desire to secure by Letters Patent is:—

- 55 1. A carton or container body of the kind referred to wherein a substantial width and/or thickness or barrier of wax or the like is interposed between the joint-forming adhesive and the interior of the body.
- 60 2. A method of making carton and like bodies as claimed in claim 1, in which the joint-forming adhesive is so applied in relation to the edge of the joint underlap as to leave a web or width of the said underlap free 65 from or unattached to the overlap and to pro-

vide for the formation of a barrier-strip of wax or proofing material between the adhesive and the interior of the body.

In testimony whereof he hereunto affixes his signature.
